CLAIM

The ornamental design for a medical dilator as shown and described.

DESCRIPTION

FIG. 1 is a front elevational view of the medical dilator; FIG. 2 is a rear elevational view thereof; FIG. 3 is a top plan view thereof; FIG. 4 is a bottom plan view thereof; FIG. 5 is a left-side elevational view thereof; FIG. 6 is a right-side elevational view thereof; FIG. 7 is a detail view of the area marked “7” in FIG. 1; FIG. 8 is a detail view of the area marked “8” in FIG. 7; and, FIG. 9 is a detail view of the area marked “9” in FIG. 7. The evenly spaced broken lines show portions of the medical dilator that form no part of the claimed design. The dot-dash broken lines forming rectangular shaped boxes around certain portions of FIGS. 1 and 7 depict areas shown as detail views in FIGS. 7, 8 and 9, and form no part of the claimed design. The appearance of any portion of the article between the jagged break lines forms no part of the claimed design.
